CLAIM

The ornamental design of the tow broadcast spreader, as shown and described.

DESCRIPTION

FIG. 1 is a perspective view of one embodiment of a tow broadcast spreader;

FIG. 2 is a front elevation view of the tow broadcast spreader of FIG. 1;

FIG. 3 is a first side view of the tow broadcast spreader of FIG. 1, the opposite side being substantially a mirror image thereof;

FIG. 4 is a bottom plan view of the tow broadcast spreader of FIG. 1;

FIG. 5 is a top plan view of the tow broadcast spreader of FIG. 1;

FIG. 6 is a perspective view of a second embodiment of a tow broadcast spreader;

FIG. 7 is a front elevation view of the tow broadcast spreader of FIG. 6;

FIG. 8 is a first side view of the tow broadcast spreader of FIG. 6, the opposite side being substantially a mirror image thereof;

FIG. 9 is a bottom plan view of the tow broadcast spreader of FIG. 6; and,

FIG. 10 is a top plan view of the tow broadcast spreader of FIG. 6.

The broken line showing of the frame and wheels is included for the purpose of illustrating portions of the tow broadcast spreader and forms no part of the claimed design.
